UNITED STATES PATENT OFFICE

124,023

DESIGN FOR A COMBINATION TOOL

George H. Gaede, Shafter, Calif.

Application October 5, 1940, Serial No. 95,667

Term of patent 14 years

To all whom it may concern:

Be it known that I, George H. Gaede, a citizen of the United States, residing at Shafter, in the county of Kern and State of California, have invented a new, original, and ornamental Design for a Combination Tool, of which the following is a specification, reference being had to the accompanying drawing, forming part thereof.

Fig. 1 is a view in side elevation of the combination tool embodying my new design;

Fig. 2 is a view in top plan;

Fig. 3 is a view in bottom plan.

I claim:

The ornamental design for a combination tool, as shown.

GEORGE H. GAEDE.
